RADIATOR CORE

Frank A. Neveu, Los Angeles, Calif.

Application August 11, 1934, Serial No. 739,453

5 Claims. (Cl. 257—130)

The present invention relates to new and useful improvements in heat transfer devices, and more particularly to that type of radiators which are adapted for use in connection with the cooling systems of automobile engines or other power plants.

An object of my invention is to provide an arrangement effecting an increased expanse of radiating surface of the radiating fins of which a 10 radiator is partially composed, whereby to increase the cooling efficiency of the radiator.

It is a further object in this connection to provide such increased radiating surface of the radiating fins without obstructing the air spaces 15 between the passageway-forming tube members, and thereby permit free passage of air through the radiator.

Another object of the present invention is to provide a radiating fin having increased radiating surface as referred to hereinabove, without, however, requiring additional material—in fact, considerably less material is required in a radiator of given size and/or cooling capacity, and consequently the cost of manufacture and weight 25 of the finished radiator is reduced by incorporating the principles of my present invention therein.

Yet another object is to provide a radiator fin of novel design, one of the advantages of which 30 is that a radiator core embodying it need not be dipped in molten solder, as is now usually done, but instead is subject to being assembled by the “baking” process to insure soldering of the several fins to their associated tube members, 35 thereby effecting a great reduction in the amount of solder required in the construction of a core.

The invention possesses other objects and advantageous features, some of which, with the foregoing, will be set forth in the following description of the embodiments of my invention which are illustrated in the drawing accompanying and forming a part of the specification. It is understood that I do not limit myself to the showing made by the said drawing and description, as I may adopt variations of the described forms within the scope of my invention as set forth in the claims.

Referring to the drawing:

Figure 1 is a fragmentary view in perspective showing a portion of a radiator core of the “honey-comb” or “cellular” type, having incorporated therein a fin embodying the principles of the present invention.

Figure 2 is a perspective view showing a small

portion of a modified form of fin, also intended for use in a radiator of the “cellular” type.

Figure 3 is a fragmentary, perspective view showing the radiating fin of the present invention adapted for use in the “tubular” type of radiator. Portions of the figure illustrating the front of the radiator are broken away the better to show the interior construction.

In terms of broad inclusion, my present invention contemplates the use of metal fabric, or wire mesh, as the material used in the construction of radiating fins for a radiator, instead of the sheet metal commonly employed for this purpose.

More specifically described, the improved radiator fin of the present invention comprises a sheet of wire fabric, preferably copper screen of suitable size of mesh, and composed of screen wire of suitable gauge and preferably round in cross section. The wire fabric is cut to proper size and bent to proper shape to meet the requirements of the radiator fin. This improved form of fin is adaptable for use in either the “cellular” type or the “tubular” type of radiator, and is susceptible to being formed into any size 25 and/or shape of fin in order to meet the requirements of any particular installation. Wire screen is available commercially in sheet form, and, on account of the smaller amount of metal necessary to form a sheet of given size, is considerably less expensive than sheet copper, which is the material now commonly employed in the manufacture of radiator fins. Of more importance, however, is the superiority of a radiator fin made of wire mesh from the standpoint of 30 35 heat-radiating efficiency as compared with a more conventional sheet metal fin.

This increase in efficiency is due to the large number of foramina defined by the interwoven wires of metal fabric such as copper screen, inasmuch as their presence insures much more intimate contact of the air flowing through the air passages between the tube members of a radiator core with the metal of the fin.

It is common practice in making fins from 45 sheet metal to deform the sheet with a large number of protrusions, corrugations, restrikes, blades, and the like, and to cut openings of various size, shape, and position in the sheet in the attempt to develop a great amount of turbulence 50 in the stream of air flowing through the core, as well as to cause contact of the flowing air with the metal of which the core is made. The purpose of resorting to such expedients is to remove as great a quantity of heat from the metal con- 55

fining the heated water as possible, the phenomena of conduction, radiation, and convection all being relied upon to perform this function and thus to effect the transference of as much heat as possible from the water or other medium within the tube members to the air flowing through the air passages. To my knowledge, however, the use of wire screen as the material from which to construct radiator fins has never before been resorted to; whereas by its use, the problem of providing means for insuring the very greatest degree of intimate contact with the metal has been met, and moreover, without interfering with or impeding the flow of air through the air passages.

15 The air is caused to pass through a much higher number of orifices than can possibly be formed in any sheet metal fin, thereby reducing the blast of air to a very large number of very fine streams of air, each of which is in very close contact with 20 the wires defining the orifice through which that stream is flowing. Each of the many wires forms a cutting edge against which the air impinges, thus causing the intimacy of contact which can be developed only by means of a cutting edge 25 exposed to air flow, and also causing turbulence, the effect of which is to direct the flow of air out of a straight path and into contact with a neighboring portion of a water tube, another fin, or another section of the same fin. These facts are 30 believed to explain partially the superiority of wire screen in the manufacture of radiator fins over sheet metal used for that purpose.

Moreover, these advantages and others can be gained without sacrifice of any of the advantageous features of sheet metal. If the design of 35 any particular make of radiator core calls for any particular configuration of fin, the wire screen is just as susceptible to being so formed as is the more conventional sheet metal. Hence 40 any desired size, shape and/or spacing of tube members may be resorted to, the fin being cut, bent, and/or otherwise formed into whatever size and shape of fin is desirable with the selected tube members.

45 Figure 1, for example, shows a small portion of a radiator core 6 made up of alternately positioned water tube members 7 and radiating fins 8, the latter of which being comprised of interwoven wire 9 of metal, preferably copper, embody 50 the principles of my present invention. Whereas the fin is adaptable to any suitable type of water tube member, each of the tube members 7 illustrated is made up of a pair of elongated strips 11 and 12 of copper the width of which coincides 55 with the thickness of the finished core. Along their edges 13 the two strips are in contact with each other and are bent to zig-zag form, whereas intermediate their edges, the strips are separated to define a water channel 14 therebetween. The 60 water channels 14 thus presented establish communication between the upper and lower header tanks (not shown) in accordance with usual practice, and hence, during operation of the device, each channel 14 has a stream of heated 65 water to be cooled flowing through it. In order to induce turbulence in the stream of water in each channel 14, and thus cause more of the heat of the water to be transmitted to the metal of the tube member, it is customary to deform 70 the metal defining the water channels, as, for example, by providing transversely extending corrugations 16 in any of several arrangements. Here the crest of each outwardly extending corrugation is preferably flattened as indicated at 75 17. Each of these flattened crests 17 provides

an area of material size contacting the associated fin 8, thereby increasing the efficiency of heat transference from the tube member to the wires of the fin, which, as will readily be understood, are very highly efficient in transferring the 5 heat to the air impinging thereagainst.

The preferred form of fin 8 for use with this type of tube member, when composed of interwoven metal wires as hereinabove disclosed, is also deformed to present a series of corrugations, 10 but, instead of extending transversely as has heretofore been the practice, the corrugations 21 of each fin 8 extend longitudinally of the core, preferably throughout the entire length thereof from the upper header tank to the lower. The 15 corrugations 21 serve to increase the effective-thickness of each fin, enabling it to hold the two adjacent tube members 7 separated and thus present an air channel 22 therebetween. Each 20 of the side walls of each longitudinally extending corrugation 21 being very porous, practically no impedance is offered thereby to the flow of air through the channel 22, in spite of the fact that very intimate contact of each particle of air with the wires of the fin is had a number of times equal 25 to twice the number of corrugations 21.

With the illustrated type of tube member 7, it is preferable to use a fin 8 wherein the corrugations 21 also are flattened at their crests 24 thus forming corrugations 21 which are substantially 30 square in cross section, and presenting relatively large areas of contact between each flattened crest 17 of each corrugation 16 of the proximal tube member 7. However, Figure 2 illustrates a modified form of fin 31 adaptable for use with 35 various other well known types of tube members of a "cellular" type core, but also embodying the present invention inasmuch as it also is constructed of wire fabric 32. This fin 31 is also corrugated, but it differs from the previously described fin 8 in that its corrugations 33 extend 40 transversely instead of longitudinally and each corrugation 33 is of triangular cross section.

In order to facilitate assembly it may in some instances be advisable to provide slight irregularities in the surface of each tube member adapted to be engaged by complementary irregularities in the surface of the proximal fin, thus serving as locators tending to hold the several members against slipping one on the other prior to and 50 during the soldering process. Such locators are illustrated in Figure 1 as taking the form of a depression or socket member 36 at each end of each crest 16 of the tube members, within which sockets are seated, raised portions or beads 37, 55 one of which is formed along the outer edge of each outer corrugation 21 of each fin 8.

Figure 3 illustrates my present invention embodied in a radiator core 41 of the "tubular" type. Here, instead of extending longitudinally of the 60 core parallel to the tube members and zig-zagging back and forth between two adjacent tube members, each fin 42, while being composed of woven wire fabric 43, extends transversely of the tubes 44, each tube 44 extending through an aperture 46 in each fin, these apertures being suitably proportioned to insure contact between each tube 44 and each fin 42. The extent of such contact can be materially increased by extending flaps 47 of the metal fabric displaced in forming 65 each aperture along the adjacent side wall 48 of the associated tube 44. Moreover, I prefer to bend the forward edge 51 of each fin 42 so as to form a flap 52 lying in a plane perpendicular to that of the remainder of the fin and ex- 70 75

tending into contact with the next adjacent fin. In this manner, the front of the radiator presents the appearance of a continuous, flat wire screen, concealing the tubes 44 therebehind and requiring that all the air passing through the air passages between tubes flow through the relatively fine apertures presented by such a screen. It is customary commercial practice in assembling cores using fins made of sheet metal to fasten the parts permanently together by dipping the assembled core in a bath of molten solder, causing the fins to be soldered to the tube members in an integral structure. It is preferable, however, when using fins embodying the present invention, to avoid the dipping process of soldering, as such method would have the tendency to clog the openings of the screen of which each fin is made. Rather, a "baking" process should be used, wherein each tube member is "tinned" before assembly, and after assembly the core dipped in a suitable acid or flux, and then the entire core placed in an oven or the like where its temperature is raised higher than the melting point of the solder. The solder already present on the tube members will flow onto the portions of the fin in contact therewith, forming a "sweated" joint fully as efficient from the standpoints of strength and heat-transference as a "dipped" joint and requiring so much less solder as to amount to a saving of from one to four or more pounds of solder per core, depending on the size of the latter. The saving in weight thus attained is material, but the reduction in cost of the core is of still greater importance, because the cost of solder is so high as to represent a very material item in the cost of the finished product. The present invention contributes in another way toward reduction of manufacturing cost for the reason that the amount of copper screen necessary to construct a fin of given size costs materially less, because of the smaller amount of metal present, than the amount of sheet copper necessary to form a fin of that same size.

I claim:

1. A radiator construction comprising a plurality of tube members disposed in spaced parallel relation, and a radiating fin disposed between each two adjacent tube members, each of said fins being composed of wire screen and corrugated to provide corrugations having their crests alternately on opposite faces of the fin, said crests making contact with the associated tube members, and said corrugations extending substantially parallel to the direction of flow through said tube members thereby disposing the side walls of the corrugations in positions extending across the air passages between said tube members.

2. A radiator construction comprising a plurality of tube members disposed in spaced parallel relation, and a radiating fin disposed between each two adjacent tube members, each of said fins being composed of wire screen and corrugated to provide corrugations having their crests alternately on opposite faces of the fin, said crests making contact with the associated tube members, and said corrugations extending substantially parallel to said tube members thereby disposing the side walls of the corrugations in positions extending across the air passages between said tube members, said tube members having irregularities in the surfaces thereof and said fins having irregularities in the surfaces thereof complementary to and engaging those of said tube members to restrain said tube members against movement relatively to said fins prior to permanent fastening thereof.

3. In a radiator construction, a core comprising a plurality of wire mesh fins disposed in spaced parallel relation, and a plurality of tube members spaced apart, each of said tube members extending through and making contact with all of said fins, said fins being bent adjacent their forward edges and each fin so bent making contact with the next adjacent fin to present a substantially continuous screen extending across the front of said core.

4. In an automobile radiator, a core comprising water tube members spaced apart to define passages through which a flow of air in a predetermined direction is induced, said water tubes extending angularly with respect to the direction of said air flow, and a fin of foraminous material interposed between each two adjacent water tube members, and corrugated to define corrugations having their crests alternately on opposite faces of the fin, said corrugations extending substantially parallel to said tubes and angularly with respect to the direction of said air flow, the crests of said corrugations contacting the associated tube members and the side walls of the corrugations extending across said air passages, whereby said flow of air is required to pass through the foramina in said side walls.

5. In a radiator construction, a core comprising a plurality of fin members of foraminous material disposed in spaced, parallel relation, and a plurality of tube members arranged in contact with said fins for transmission of heat therebetween, said fins being bent adjacent edges thereof to present portions lying in the plane of the associated face of said core and contacting the next adjacent member whereby all air going through the spaces between said tube members is required to flow through at least one thickness of said foraminous material.
